UNITED STATES PATENT OFFICE.

PAUL A. GOLNIK, JOHN JOSEPH TOOLAN, AND GEORGE HARRED, OF CHICAGO, ILLINOIS, ASSIGNEES TO SPIEGEL, MAY, STERN COMPANY, OF CHICAGO, ILLINOIS, A CORPORATION OF ILLINOIS.

PLATEN.

Application filed January 24, 1927. Serial No. 163,172.

This invention relates to printing mechanisms, and particularly to platens of the kind which are movable to bring the sheet or other work into engagement with the 5 stencil or other form for making the impression.

The common platens of this class heretofore in use had a positive action which did not permit any variation in the lengths of 10 their strokes, that is, they generally moved a predetermined distance, irrespective of the thickness of the work being operated upon, with the result that the impressions varied with the thickness of the sheets.

15 The main objects of this invention are to provide an improved form of platen; to provide improved means for positively supporting the platen so as to secure it against any yielding action during the printing 20 operation; to provide improved mechanism for moving the platen toward the impression element; to provide improved driving means 25 for actuating said mechanism; to provide improved means for yieldingly connecting said driving means with said mechanism so as to permit automatic variation of the platen's stroke to compensate for sheets of 30 different thicknesses; and to provide a platen of this kind which is particularly 35 adapted for use in connection with addressing machines.

An illustrative embodiment of this invention is shown in the accompanying drawings, 40 wherein,

35 Fig. 1 is a fragmentary, vertical section of an addressing machine to which an improved platen is applied.

Fig. 2 is a transverse, vertical section 45 taken on the line 2—2 of Fig. 1, and showing the improved mechanism for actuating the platen and the driving means therefor.

Fig. 3 is a transverse, vertical section, 50 taken on the line 3—3 of Fig. 1.

The common form of addressing machine 55 to which this invention may be applied comprises a horizontal guideway along which the stencils are moved to a printing position between an impression element and a platen. The impression element is generally located

above the guideway and is controlled in its 50 operation by suitable selector mechanism. The platen is usually located below the guideway for lifting the envelopes or other sheets into contact with the stencil.

Inasmuch as this invention relates particularly to the platen and its operating mechanism, only that part of an addressing machine which is believed necessary to a complete understanding of the invention has been illustrated in the accompanying 55 drawings.

In the form shown, the addressing machine, to which an improved platen has been applied, comprises a stationary frame having a horizontal table 1, on which is mounted a guideway 2, along which stencils 3 are fed in a step-by-step movement to a printing position beneath an impression member 4, which is movable toward and away from the 60 stencil by suitable mechanism, not shown.

The guideway 2 is spaced from the table 1 so as to permit envelopes 5 to be inserted 65 into printing position below the stencil being acted upon. Formed in the table 1 directly below the impression member 4, is an opening 6 through which extends a vertically movable platen 7.

The platen 7 is provided with a pair of depending legs 8, which are slidable in guideways 9 formed on a pair of bearing 70 members 10 mounted on the lower face of the table 1. The lower ends of the legs 8 are bifurcated so as to straddle a horizontal shaft 11 journaled in the bearings 10. Journaled on the lower side of the platen 7, is a 75 roller 12 which rests on a rotary cam 13 fixed on the shaft 11. The cam 13 positively supports the platen and also moves it toward the impression member 4 when the shaft 11 is rotated in one direction.

When the shaft 11 is rotated in the opposite direction, the cam 13 moves into position to permit the platen to move by gravity away from the impression member. The outer end of the shaft 11 is journaled in a bracket 80 14 mounted on the lower side of the table 1. The mechanism for oscillating the shaft 11 comprises a gear segment 15 pivoted to

the bracket 14 by a pin 16 and meshing with a pinion 17 fixed on the shaft 11. Formed on the segment 15, is an arm 18 which is connected to the driving means for imparting a rocking movement to the gear segment.

The driving means for actuating the segment 15 comprises a shaft 19 journaled on a bracket 20 and having fixed thereon a crank 21 adapted for continuous rotation in one direction. The shaft 19 may be driven by the same motor which drives the stencil feeding and printing mechanism, not shown. Connected to the crank 21, is a link 22 which extends downwardly through an opening 23 in the table 1. Mounted on the lower part of the link 22, is a fixed collar 24 and a movable collar 25. Embracing the link 22, and bearing between the collars 24 and 25, is a spring 26, the tension of which may be adjusted by an adjusting nut 27 engaging the collar 25.

The collar 25 is pivotally connected with the arm 18 of the gear segment 15 so that, when the link 22 moves downwardly, a variable movement is imparted to the gear mechanism and platen through the spring 26.

In operation, the stencils 3 are fed in a step-by-step movement along the guideway 2 so as to bring the stencils successively into printing position below the impression member 4. When the stencil reaches printing position, the inking member 4 moves downwardly to engage the upper face of the stencil and the platen 7 is urged upwardly under the action of the cam 13 to raise the top envelope into position to receive the impression. When the platen 7 has been moved upwardly a sufficient distance to bring the top envelope into firm contact with the stencil, the pressure on top of the platen counterbalances the action of the spring 26 so that the gears 15 and 17 and cam 13 stop rotating. The link 22 may then continue to the limit of its down stroke without further moving the platen.

With this improved construction and arrangement of parts, a variable movement is imparted to the platen to accommodate envelopes of different thicknesses so that the impressions are always uniform, irrespective of the number of envelopes or sheets supported between the platen and the stencil. The platen is positively supported at every position in its stroke so as to be secured against any yielding action during the printing action.

Although but one specific embodiment of this invention has been herein shown and described, it will be understood that numerous details of the construction shown may be altered or omitted without departing from the spirit of this invention as defined by the following claims.

We claim:

1. A device of the class described comprising

ing a movable platen, mechanism for actuating said platen, driving means for said mechanism, and a resilient connection between said mechanism and means.

2. A device of the class described comprising 70 a movable platen, means for positively supporting said platen in any position in its stroke, mechanism for actuating said platen, driving means for said mechanism, and a resilient connection between said driving means 75 and mechanism.

3. A device of the class described comprising 80 a movable platen, means for positively supporting said platen, driving means for moving said supporting means to actuate said platen, and a yielding connection between said driving and supporting means.

4. A device of the class described comprising 85 a movable platen, means for positively supporting said platen, mechanism for moving said supporting means to actuate said platen, driving means for said mechanism, and a yielding connection between said driving means and mechanism.

5. A device of the class described comprising 90 a movable platen, a cam for supporting said platen, driving means for moving said cam to actuate said platen, and a yielding connection between said driving means and cam.

6. A device of the class described comprising 95 a movable platen, a rotary cam for supporting said platen, mechanism for rotating said cam to actuate said platen, driving means for said mechanism, and a yielding 100 connection between said driving means and mechanism.

7. A device of the class described comprising 105 a movable platen, a rotary cam arranged to support said platen, gear mechanism for rotating said cam to move said platen in one direction, driving means for said gear mechanism, and a resilient connection between said driving means and mechanism.

8. In a printing device, the combination 110 with an impression member, of a platen movable toward and away from said member, a rotary cam arranged to support said platen, gear mechanism for rotating said cam to move said platen in one direction, and driving means providing a variable movement for said mechanism.

9. In a printing device, the combination 115 with an impression member, of a platen movable toward and away from said member, a rotary cam arranged to support said platen, gear mechanism for rotating said cam to move said platen toward said impression member, said platen being movable away from said member by gravity, and driving 120 means providing a variable movement for said mechanism.

10. A device of the class described comprising 125 a rotatable shaft, a cam fixed on said shaft, a movable platen supported by said

cam, a pinion fixed on said shaft, a gear segment meshing with said pinion, driving means for oscillating said segment to actuate said platen, and a yielding connection between said driving means and segment.

11. A device of the class described comprising a rotatable shaft, a movable platen having bifurcated arms straddling said shaft, a roller on said platen, a cam fixed on said shaft in position to coat with said roller for supporting said platen and for moving it in one direction, a pinion on said shaft, a gear segment meshing with said pinion, and driving means for oscillating said segment.

12. In a device of the class described, the combination with an impression member, of a platen movable toward and away from said member, mechanism providing a variable movement for the platen in the direction of said impression member to accommodate different thicknesses of the work operated upon, and means for positively supporting said platen in any position in its stroke.

Signed at Chicago this 20th day of January, 1927.
